Primary Examiner — Omeed Agilee*Assistant Examiner* — David Truong(74) *Attorney, Agent, or Firm* — Muncey, Geissler, Olds & Lowe, P.C.; Leo V. Gureff(57) **CLAIM**

The ornamental design for a bottle, as shown and described.

DESCRIPTION

FIG. 1 is a front perspective view of a bottle according to the present invention; and,

FIG. 2 is a front perspective view of the bottle according to the present invention with the lid removed.

The broken lines and the lower opacity areas within the broken lines show portions of the bottle that form no part of the claimed design.
